UNITED STATES PATENT OFFICE.

RALPH S. PIPER, OF CHICAGO, ILLINOIS.

TRANSFORMER.

Application filed April 3, 1925. Serial No. 20,510.

Radio apparatus of all kinds has recently been subjected to critical structural examination with a view to effect more complete and more accurate transmissions. During the 5 early period of development, radio investigations were confined mostly to circuit relations and the perfecting of the three electrode tube. These latter details have been worked out, if not to final form, at least sufficiently well to 10 give reliable and efficient results, and to require corresponding improvements in the structural design of the several elements of a radio circuit.

My invention relates to improvements in 15 the mounting of a transformer, especially adaptable to use as a coupler element between the several stages of a radio frequency amplification system, although these improvements are applicable also in power circuit 20 work to transformers, inductances, and induction coils.

One object of my invention is to do away 25 with large masses of di-electrics as supporting parts for the operative parts of electrical apparatus.

Another object is to permit the use of very light operative parts and yet insure that such parts maintain their relative alignments.

Another object is to free inductive elements 30 from local capacity effects, and to reduce leakage and di-electric absorption losses. Other objects will appear as the description of my invention is given in connection with the accompanying drawings, which constitute part of this specification.

Fig. 1 is a longitudinal elevation, part sectional, of a transformer which embodies my invention.

Fig. 2 is a cross-sectional view on the line 40 1—1 of Fig. 1.

Fig. 3 is a perspective view of a transformer of my invention.

Fig. 4 is a side elevation of a modification of my improved transformer.

Fig. 5 is a plan view of the transformer shown in Fig. 4, normal to its principal axis.

Fig. 6 is a side view of a modified detail of the parts shown in Fig. 5.

Various expedients have been proposed to 50 render coils used in radio apparatus self-supporting. Aside from being wasteful of space, these devices almost invariably violate the fundamental law of magnetic induction which requires wires should be closely assembled to create strong effects with freedom from distortion. I have designed the coil

structures of my invention primarily to give excellent electrical results, and have combined with such coils supporting parts that permit the coils to continue to discharge their 60 primary functions indefinitely, with practically complete freedom from both energy losses and distortion.

In my prior Patent 1,438,854 of date Dec. 12, 1922 I disclosed and claimed a disposition 85 of windings adapted to influence each other according to the best possible conditions under which magnetic induction can take place from one winding to another, and the improvements of this application are directed to 70 utilize the principles of the patent referred to as applied to coils which operate without being impeded in their action by the harmful effects of di-electric masses, used as supports for the windings.

In the drawings like reference characters are used on the several views to indicate the same parts.

Referring to Fig. 3, I have shown therein the general assemblage of coils structure and 80 supporting parts. In this figure 8 is a cylindrical coil of very fine copper wire, the turns of which extend between a series of bosses integral with side rings 1. The bosses 4 serve as sockets for rods 3 which confine the coil 8 85 circumferentially, see Fig. 2. The rods 3 are carried eccentrically in the bosses 4, so as to provide considerable flat surface for the edge of the coil 8 to impinge upon. It will be noted, however, that there exists only a line 90 contact between the coil and its supports. The material of the supports is insulating, preferably bakelite. The rings 1 which carry the bosses 4 constitute the skeleton upon which the operative coils are hung, and it 95 will be apparent that these rings not only act as sturdy supports, but are so located that they are well out of the magnetic and electrical fields set up by the coils when in action, and hence energy losses and distortions are 100 avoided.

As shown in Figs. 1 and 2, coil 7 has only a fraction of the number of turns of coil 8, both coils being single layer wound. Using coil 8 as a primary it will be free to set up as nearly 105 perfect a cylindrical field as if it were a solenoid, and as such fields are known to be most uniform at their extreme ends, the device will act with great perfection as a coupler between tube circuits with tuned radio frequency stage circuits, and I have found it to give very exceptional results in such an appli- 110

cation. Part of this success is due to the character of the coupling between the coils, as explained in my earlier patent. It may be particularly pointed out here, however, that the 5 effect of the alternate very close and very open coupling between the sections of windings 7 and 8 is of peculiar importance in tuned stage circuit coupling because any distributed capacity of the close coupled sections must act 10 in series with respect to the winding as a whole, and the harmful effects of two such distributed capacities in series will be very much less than it would be if acting as a continuous distributed capacity, throughout the winding.

15 Fig. 4 shows a modification of my invention in which the supporting rings 1 are connected by two T shaped bars, which are moulded integrally with the rings. These bars 10 may be solid T bars but I prefer to fashion them with 20 a number of oblong apertures 12 which operate to cut down absorption losses and leave the bars practically as strong as if solid. Each bar presents a thin straight edge portion towards the axis of the rings and these edges 25 may be rounded. These bars act similarly to the rods 3 of Figs. 1 and 2 to hold the coil 8 with its axis in the axis of the rings 1.

Besides the two integral bars 10 the rings 1 are further connected together by a removable bar 14, also having a general T shape. 30 This bar 14 is provided with end plates 18, see Fig. 5, which may be riveted to the rings 1 by rivets 13. The removable bar 14 provides a ready means for assembling the coil in its 35 supporting unit, and allows of its manufacture as a unit by itself. Fig. 6 shows a modification of the removable bar showing slots 16,

cut by a milling cutter after the bar is moulded. The cutter gives the precise contour and size to the slot to enable it to take the ring 1 40 moderately tight. In this form the rings 1 may be cemented in place.

The bar 14 carries a lug 17 which is slotted to receive a bracket 9. This bracket has a screw hole 19 directly under the center C of 45 the coil 8. By reason of this relation the coil may be initially adjusted with respect to its mates in the successive stages of amplification to effect a cancellation of stray fields, after which the bracket may be fixed in position 50 through hole 20.

It will be seen from the above description of coils and their supporting parts that the coils are not only held in the exact position desired, but they are well protected from accidental 55 injury.

What I claim as my invention is:

1. In a radio transformer, a coil and a dielectric support therefor comprising a frame made up of apertured end members, connected together by tie bars provided with end 60 lugs, said tie bars engaging the external surface of the coil by line contact, and said lugs spacing the coil from the end members of the frame also by line contact with the coil. 65

2. A radio frequency transformer, comprising a coil structure, a supporting frame for said coil engaging the coil at exterior surface points on the coil, and fixation means for said frame designed to permit the coil to be adjusted and fixed in various positions around a line 70 passing through its center of figure.

RALPH S. PIPER.
